UNITED STATES PATENT OFFICE.

CHARLES H. GAIL, OF CINCINNATI, OHIO, ASSIGNOR TO THE SHOTT MANUFACTURING COMPANY, OF CINCINNATI, OHIO, A CORPORATION OF OHIO.

BOX BEDSPRING.

Application filed April 7, 1922. Serial No. 550,378.

To all whom it may concern:

Be it known that I, CHARLES H. GAIL, a citizen of the United States, residing at Cincinnati, in the county of Hamilton and State of Ohio, have invented certain new and useful Improvements in Box Bedsprings, of which the following is a specification.

My invention relates to bed-springs and similar cushion structures but concerns more especially constructions of this general type having fabric or other covers to keep out the dirt and to give the appliance a neat and finished appearance.

Stated somewhat differently, the invention, while pertaining to bed-springs, has especial adaptability for advantageous employment in the so-called box bed-springs of well known character.

One aim of the invention is the provision of a bed-spring or other cushion or resilient structure having a fabric cover which may be easily applied thereto and readily removed therefrom to facilitate its being washed and cleaned.

Such cover is desirably made in two parts, one for the top and major portions of the sides and ends of the bed-spring, and a companion one for the bottom and remainder of the sides and ends of the structure.

This general plan is not broadly new, but the manner in which such cover sections are attached to the bed-spring and the construction of the latter which facilitate the mounting of the cover parts are novel and possess marked benefits.

Another purpose of the invention is the production of a construction of this form which is simple in structure, which is economical to manufacture, which may be used with advantage, and which because of its obvious favorable structural characteristics commends itself to the housewife.

To enable those skilled in this art to fully understand the invention and its beneficial features when incorporated in physical form, I have illustrated a desirable and preferred embodiment thereof in the accompanying drawing forming a part of this specification and throughout the several views of which like reference numerals have been employed to designate the same structural parts.

In this drawing:

Figure 1 is a fragmentary, vertical cross-

section through an end portion of a box bed-spring incorporating in its structure the valuable parts of the invention;

Figure 2 is a similar, horizontal section on line 2—2 of Figure 1, the parts being viewed in the direction indicated by the arrows;

Figure 3 is a partial plan view of a marginal section of the upper fabric cover showing some of its attachment hooks;

Figure 4 illustrates a portion of the hook-equipped margin of the lower or bottom cover; and

Figure 5 is an enlarged section through the latter cover indicating the manner of mounting and covering the hooks thereon.

By reference to Figure 1 of the drawing, it will be perceived that in this particular embodiment of the invention the end-bar 11 of the bed-spring frame is in the form of an angle-bar disposed with its lower horizontal flange projecting inwardly, its other or complementary flange extending upwardly, as is clearly shown.

At intervals, this vertical flange has fastened against its inner face a plurality of spaced, parallel, right-angle bars 12, 12, one arm of each of which projects outwardly some little distance beyond and above the frame bar 11, the outer ends of such arms being united and tied together by a flat, longitudinally-disposed, marginal bar 10 riveted thereto, such overhanging skeleton frame part of the structure affording convenient means for supporting the box bed-spring on the bedstead, not shown.

Near its bend or elbow, each of such brackets 12 has a smaller, inwardly-extended, apertured angle-bracket 13 riveted against its inner surface to afford by reason of their holes or eyes attachment or supporting elements for the ends of short, horizontal, helical springs 14 which connect longitudinal wires 15 to such brackets, these wires acting to join together and prevent displacement of the middle, reduced-size portions of the main, upright, hour-glass spiral-springs 16, the lower ends of which may be mounted on the frame and connected together in any approved fashion.

Mounted or residing in the small, aligned gaps or clefts between the pairs of brackets 12 and 13 at their bends in opposite directions, I employ a rod or wire 17 which ex-

tends completely around the bed-spring frame although only a portion of it is illustrated in the drawing.

The bed-spring includes also a series of 5 shorter, upright, tapered, border spiral-springs 18, one above and mounted on each pair of brackets and the associated wire or rod, the lower coil of each such spring extending beneath both brackets but above the 10 rod or wire whereby such bottom end of the spring is firmly supported and anchored in place.

The top coils of the many spiral-springs 16 and 18 are joined or connected together 15 in any suitable way, as by means of short, helical springs 19, and the upper coils of the outer springs 18 are secured to a border or marginal rod or wire 20 by appropriate fastening or connecting wires 21.

20 A pad or thin mattress 22 rests on the bed-spring, its edge portions being down-turned around the border member 20 as is indicated in Figure 1, and the bed-spring as a whole is supplied with a fabric cover 23 25 of suitable shape to fit over the pad, enclose the upper portions of the sides and ends of the spring, and extend inwardly beneath the outstanding brackets 12.

The edges of such cover element are 30 equipped with hooks 24 which take around the rod or wire 17 and hold the cover securely but detachably or demountably in place, such hooks conveniently being like or similar to the hooks used on shoes for 35 cooperation with the shoe lacing, one of such hooks fastened to the other cover member about to be described being shown in Figure 5.

Such companion or complementary fabric 40 cover element 25 is of a shape to encase the bottom of the bed-spring and those portions of the sides and ends not enclosed or concealed by the top cover, and its top margin is fitted with like hooks 26 also designed to 45 engage and cooperate with the same wire or rod 17 to hold the bottom cover in place but yet in a manner permitting its ready removal when desired.

The hooks or securing elements 24 are 50 nearer the edge of their cover than the hooks 26 are on their cover, thereby by reason of the slight stretching of the former fabric in hooking it in place permitting the application of the hooks of the latter fabric to 55 the wire or rod between the other hooks all as is clearly depicted in Figure 2 and enabling the margin of the lower cover to overlie all otherwise uncovered spaces near the wire.

60 It is of course more or less immaterial which cover shall be innermost or outermost at the point of attachment or hooking, it being merely desirable to completely enclose or encase the bed-spring as a whole.

65 The sides of the bed-spring are of much

the same construction as the ends and hence require no illustration, the two covers being fastened at the sides in the same manner as they are at the ends, the two wires or rods 17 and 20 being of rectangular shape extending completely around the structure. 70

It will be clear from the above that the manner in which the desired objects are attained through the employment of this invention, will commend itself by reason of 75 the structural advantages inherent in the appliance, but it is to be borne in mind that the invention is not limited or restricted to the precise details of structure presented because these may be changed more or less 80 radically without departing from the substance of the invention as defined by the appended claims and without the sacrifice or loss of any of its substantial benefits and 85 advantages.

It will be observed that in the embodiment 90 of the invention herein presented, the margins or borders of the two cover members are demountably attached to the same securing or holding member and they may be 95 easily taken off for cleaning purposes and as readily replaced.

In a certain sense the wire or rod with which the cover hooks coact constitutes a 95 part of the bed-spring frame, being locked in position thereon and thereto by the associated spiral-springs.

I claim:—

1. In a spring structure of the character described, the combination of a frame, a rod 100 supported on and forming a part of said frame, a spring-cushion composed of upright spiral springs mounted on said frame with a portion of the springs interlocked with said rod and locking the latter to the 105 frame, a cover for the upper portion of the structure, a cover for the lower portion of the structure, and means to detachably fasten both covers to said rod.

2. In a spring structure of the character 110 described having an upper portion overhanging the lower portion, the combination of a frame, a rod supported on and forming part of said frame substantially at the junction of the overhanging part of the spring structure with its lower part, a spring cushion mounted on said frame, a cover encasing the upper portion of the structure including the overhanging part, a second cover encasing the lower portion of the 115 structure, the two covers substantially entirely encasing the spring structure, and means detachably fastening each of said covers to said rod.

3. In a spring structure of the character 125 described, the combination of a frame, a plurality of pairs of oppositely-extended brackets fastened to said frame, a rod mounted on said brackets substantially at their junctions, a cover encasing the upper por- 130

tion of the structure and having hooks detachably fastening the cover to said rod, and a second cover encasing the lower portion of the structure and having hooks detachably fastening it to said rod.

4. In a spring structure of the character described, the combination of a frame, substantially right-angle brackets fastened in spaced relation to said frame and projecting outwardly beyond said frame, inwardly projecting brackets secured to said first brackets, a rod carried by and between said pairs of brackets, a spring cushion carried by said frame including marginal upright spiral-
- 10

springs having their lower ends interlocked with said brackets and rod, an upper cover encasing the top, sides, ends, and overhanging bottom of the upper portion of said structure and having hooks detachably fastening the cover to said rod, and a second lower cover enclosing the bottom and lower portions of the sides and ends of the structure and having hooks demountably fastening said second cover to said rod.
